UNITED STATES PATENT OFFICE.

EUGENE T. KEPNER, OF HELENA, MONTANA.

COAL-CAR

1,357,994.

Specification of Letters Patent. Patented Nov. 9, 1920.

Application filed April 12, 1919. Serial No. 289,641.

To all whom it may concern:

Be it known that I, EUGENE T. KEPNER, a citizen of the United States, residing at Helena, in the county of Lewis and Clark 5 and State of Montana, have invented new and useful Improvements in Coal-Cars, of which the following is a specification.

This invention relates to new and useful improvements in dumping cars and the 10 principal object of the invention is to provide means whereby the car may be tilted sidewise to discharge its load.

Another object of the invention is to form the car of a plurality of sections, each section being independent of the other sections and each section being capable of being dumped independently of the other sections.

The invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the several views, and in which:—

Figure 1 is a side view of a car constructed according to my invention.

Fig. 2 is an end view.

Fig. 3 is a cross section.

Fig. 4 is a longitudinal section.

Fig. 5 is a detail view.

In these views, 1 indicates the base, supported by the usual trucks 2. At each end of the base are located upright frames 3 and 40 similar frames 4 are located intermediate the ends of the base. These upright frames are suitably braced by interior rods. The upper ends of the frames support the roof 5 of the car. This roof consists of the flat 45 central portion 5' which is rigidly connected with the frames, and the inclined sides 5x. These sides are provided with large openings closed by doors 16, which have their upper ends hinged to the edges of the flat 50 portion 5'. If desired the sides may be omitted entirely and the doors made large enough to constitute said sides. The ends of the roof are closed by the sheets 17 carried by the upper ends of the end frames 3.

Semi-elliptical springs 6 are suitably secured to the base 1, and a horizontal shaft 7 is secured to the centers of said springs and said shaft is rigidly connected with the springs so as to be prevented from rotation.

The car body is formed of a plurality of independent sections 8, each of which consists of the bottom 9 and the sides 10. The top of each section is open. The under side of the bottom 9 of each section is secured to the shaft 7 in such a manner that said section may have rotary movement on said shaft. Collars 12 may be formed on the shaft to prevent the sections from moving lengthwise of the shaft.

To prevent the sections from tilting I provide arms 13, pivoted at their lower ends to the upright frames and having their upper ends engaging in brackets 14 secured to the bottoms of the sections. The pivot 75 bolts pass through slots 13' formed in the arms, as shown in Fig. 5. By pressing these arms to cause them to rotate on the pivot bolts they will be disengaged from the brackets so that the sections may be tilted. 80

The sides of the sections are provided with doors 15, hinged at their upper ends so that when the sections are tilted the doors will swing outwardly and thus permit the load to discharge. Any suitable means may 85 be used for locking the doors.

I prefer to make each section of greater width than its length so that the sections may be tilted with but slight effort.

It will be seen that the sections may be 90 quickly and easily filled through the doors in the roof and that the sections can be quickly discharged by tilting to either side. As each section is tilted to one side its opposite side will strike the door 16 and raise 95 the same so that the doors will not interfere with the tilting of the sections.

The springs must be high enough to support the bottoms of the sections a sufficient distance above the base to prevent said base 100 from interfering with the tilting action. The tops of the sections project a slight distance above the lower edges of the roof so that said roof will prevent rain and snow from entering the sections.

It will also be seen that the sections can be filled and discharged independently of each other and from either side of the track,

It is thought from the foregoing description that the advantages and novel features of my invention will be readily apparent.

I desire it to be understood that I may make changes in the construction and in the combination and arrangement of the several parts, provided that such changes fall within the scope of the appended claims.

I claim as my invention:

- 10 1. A dump car comprising a wheeled base, a frame on the base, a roof the horizontal portion of which is rigidly supported by said frame and a body tiltably supported on the base under the roof.
- 15 2. A dump car comprising a wheeled base, upright frames supported thereon, a roof supported by said frames, upwardly swinging doors forming portions of said roof and a body tiltably supported on the base under the roof.
- 20 3. A dump car comprising a wheeled base, upright frames supported thereon, a roof supported by said frames, upwardly swinging doors forming portions of said roof, a

body tiltably supported on the base under 25 the roof and doors in the sides of said body and hinged at their upper ends.

4. A dump car comprising a wheeled base, upright frames located on said base, a roof supported by the frames, upwardly swing- 30 ing doors forming portions of said roof and a plurality of body sections tiltably sup- ported on the base between the frames and arranged under the roof.

5. A dump car comprising a wheeled base, 3 upright supporting frames thereon, a roof supported by said frames, hinged doors forming portions of the roof, springs located on the base between the frames, a longitudinally extending shaft carried by said 40 springs, body sections pivotally connected with the shaft and arranged between the frames, and below the roof and means for normally holding the sections against tilt- 45 ing movement.

In testimony whereof I affix my signature.

EUGENE T. KEPNER.
